UNITED STATES PATENT OFFICE.

BARNARD M. CHASE, OF HUDSON, NEW YORK.

RAILROAD-SPIKE.

SPECIFICATION forming part of Letters Patent No. 657,513, dated September 11, 1900.

Application filed June 18, 1900. Serial No. 20,741. (No model.)

To all whom it may concern:

Be it known that I, BARNARD M. CHASE, a citizen of the United States, residing at Hudson, in the county of Columbia and State of New York; have invented a new and useful 5 Railroad-Spike, of which the following is a specification.

This invention relates to spikes, and has for its object to provide an improved device of this character to form a track-fastening for securing the rails to the ties or sleepers.

It is furthermore designed to provide a railroad-spike of peculiar shape which facilitates the driving thereof and insures a straight setting of the spike, takes a firm hold upon the wood, so as to prevent the spike from working loose, and at the same time may be readily drawn without bending the spike, thus permitting of the latter being again used.

With these and other objects in view the present invention consists in the combination and arrangement of parts, as will be hereinafter more fully described, shown in the accompanying drawings, and particularly 25 pointed out in the appended claim, it being understood that changes in the form, proportion, size, and minor details may be made within the scope of the claim without departing from the spirit or sacrificing any of 30 the advantages of the invention.

In the drawings, Figure 1 is a perspective view of a railroad-spike formed in accordance with the present invention. Fig. 2 is a side elevation thereof. Fig. 3 is an edge elevation of the spike. Fig. 4 is a transverse 35 sectional view taken on the line 4 4 of Fig. 2.

Corresponding parts in all of the figures of the drawings are designated by like characters of reference.

Referring to the accompanying drawings, 1 designates the shank of the spike, which is rectangular in cross-section and is provided with the usual head 2, the forward portion 3 of which projects laterally in front of the 45 shank, so as to overhang the flange of a rail in the ordinary manner. In order to better distinguish the several sides of the spike, I will term the sides 4 and 5 the "front" and "rear" sides, respectively, which are smooth 50 for their entire lengths, and thereby free from projections of any character; also, the lower portions 6 and 7 of these sides are bev-

eled inwardly, so as to form a chisel-point or sharp end 8. The opposite edges of the shank are provided with a plurality of projections 9, the opposite longitudinal faces 10 of which are beveled so as to converge and meet in a straight sharp edge midway between the opposite front and rear sides of the spike. As shown in the drawings, each 55 edge has three such projections, of which the upper two have their opposite ends 11 beveled so as to converge outwardly, and thereby form inclined shoulders. The lowermost projection is considerably longer than the 60 others, as it extends to the lowermost extremity of the shank, and instead of having its lower end terminated in an inclined shoulder the sharp edge formed by the opposite beveled faces 10 is extended and inclines inwardly, as at 12, to the adjacent end 65 of the chisel-point of the shank. As best illustrated in Fig. 2, it will be seen that the uppermost projection terminates short of the head of the spike, so as to facilitate the application of a claw beneath the head for the 70 purpose of drawing the spike from a tie.

From the foregoing description it will be seen that the front and rear sides of the spike have no projections to interfere with the 75 driving thereof, and the front side may be arranged in close proximity to the flange of a rail, so that the head may overhang the same. Also the comparatively-long beveled ribs at the point of the spike insure the straight 80 driving thereof and prevent the same from being twisted, while the beveled ends of the other ribs or projections offer but slight resistance in the driving of the spike, and the sockets or recesses formed by the adjacent 85 beveled ends of the projections receive the fibers of the wood when the latter expands after the passage of the rib, whereby the spike is firmly gripped by the wood, and thereby held against accidentally working 90 loose. As in the driving of the spike the lower inclined shoulders offer slight resistance, the upper shoulders offer slight resistance when the spike is being drawn out of the wooden tie, and the former may be drawn 95 without the employment of a fulcrum for the claw-bar or other instrument, whereby the spike is not bent and is in condition for immediate use.

What is claimed is—

A railroad-spike, comprising a substantially-rectangular shank, having a head, which projects laterally at the forward side thereof, the front and rear sides of the shank being free from projections, and the opposite edges of the shank having a plurality of longitudinally-aligned projections or ribs, the opposite longitudinal sides of which are beveled and intersect substantially midway between the opposite sides of the spike, the opposite lowermost ribs having their sharp longitudinal edges inclined inwardly toward the point of the spike, and their upper ends bevelled and intersect substantially midway be-

veled upwardly and inwardly, the opposite ends of the other ribs having their opposite ends beveled to converge outwardly, and the adjacent beveled ends forming sockets or recesses, the uppermost ribs terminating short of the head.

20

In testimony that I claim the foregoing as my own I have hereto affixed my signature in the presence of two witnesses.

BARNARD M. CHASE.
